UNITED STATES PATENT OFFICE.

GUSTAVE L. HERZ, OF VIENNA, AUSTRIA-HUNGARY.

ELECTRIC-CABLE TERMINAL.

1,139,973.

Specification of Letters Patent.

Patented May 18, 1915.

Application filed March 25, 1913. Serial No. 756,720.

To all whom it may concern:

Be it known that I, GUSTAVE L. HERZ, a subject of the Emperor of Austria-Hungary, and resident of Vienna, Austria-Hungary, have invented a new and useful Improvement in Electric-Cable Terminals, of which the following is a specification.

The object of this invention is to provide novel features of construction whereby an electric cable terminal may be securely fastened to the cable in a very neat and simple manner, in which the terminal may be rapidly brought into and out of engagement with the spark plug electrode and in which the spark plug insulator is well protected.

A practical embodiment of my invention is represented in the accompanying drawings, in which—

Figure 1 represents the terminal in side elevation, the terminal being shown secured to the cable and attached to a spark plug, Fig. 2 is a longitudinal central section through the cable and terminal, the spark plug being shown in side elevation, and Fig. 3 is a view similar to Fig. 2 showing a slightly modified form in which the spark plug electrode receiving socket piece is held in place by molding it into the casing rather than by securing it by means of a separate fastening device, as shown in Figs. 1 and 2.

The spark plug is denoted as a whole by 1, its electrode by 2 and its insulator by 3. The electric conducting cable comprises the usual core 4 and the protective covering 5. The terminal comprises a casing 6 and conducting socket piece 7 having a socket 8 for removably receiving the spark plug electrode 2. The walls of the socket 8 are preferably slit to form spring tongues 9 for frictionally engaging the electrode 2.

The casing 6 is made of non-conducting material, such as rubber compound, and the socket piece 7 is made of conducting material, such, for instance, as brass. In the form shown in Figs. 1 and 2 this socket piece 7 is held within a recess 10, formed in the casing 6, by means of a screw 11 which passes through the casing into the said socket piece. In the form shown in Fig. 3

the socket piece is molded or otherwise secured in its recess 10 without the use of an exterior fastening device. The cable 5 is inserted into a recess 12 formed in the casing 6. In the present instance, this recess 12 is shown at right angles to the recess 10. An electrical connection is formed between the core 4 of the cable 5 and the socket piece 7 and the terminal is at the same time secured to the cable by means of a wood screw 13 which passes through the casing 6 and a hole 14 in the socket piece into engagement with the wires which form the core 4 of the cable. The casing 6 has a protective skirt 15 surrounding the socket piece 7 and extending outwardly from the casing a sufficient distance to form a protection for the insulator 3 of the spark plug.

It is evident that slight changes might be resorted to in the form, construction and arrangement of the several parts without departing from the spirit and scope of my invention; hence I do not wish to limit myself strictly to the structure herein set forth, but

What I claim is:—

1. A cable terminal comprising a conducting socket piece for removably receiving a spark plug electrode, a non-conducting casing having a cable receiving recess and a wood screw arranged to pass through the casing and socket piece into engagement with the cable for holding the cable within the casing in electrical contact with the socket piece.

2. A cable terminal comprising a conducting socket piece for removably receiving a spark plug electrode, a non-conducting casing having a cable receiving recess and a socket piece receiving recess, a screw arranged to pass through the casing and socket piece into engagement with the cable and a screw arranged to pass through the casing into engagement with the socket piece for holding it in its recess.

3. A cable terminal comprising a conducting socket piece having means for frictionally engaging a spark plug electrode, a non-conducting casing having a cable receiving recess and a socket piece recess, a screw ar-

ranged to pass from one side of the casing through the socket piece into engagement with the cable on the other side of the casing and a screw arranged to pass through the 5 casing into engagement with the socket piece for holding it in its recess.

In testimony, that I claim the foregoing

as my invention, I have signed my name in presence of two witnesses, this third day of March 1913.

GUSTAVE L. HERZ.
